(57) **CLAIM**

The ornamental design for a baseboard heater, as shown and described.

DESCRIPTION

FIG. 1 is a perspective view of a baseboard heater showing our new design;

FIG. 2 is a front view thereof;

FIG. 3 is a left side elevation view thereof;

FIG. 4 is a right side elevation view thereof; and,

FIG. 5 is a top plan view thereof.

The broken lines in FIG. 2 depict portions of the baseboard heater that form no part of the claimed design.

1 Claim, 5 Drawing Sheets
